UNITED STATES PATENT OFFICE.

HOMER LITCHFIELD, OF NORTH ADAMS, MASSACHUSETTS, ASSIGNOR OF ONE-HALF TO ENOCH H. BEER, OF SAME PLACE.

LET-OFF MECHANISM FOR LOOMS.

SPECIFICATION forming part of Letters Patent No. 379,173, dated March 6, 1888.

Application filed May 17, 1887. Serial No. 238,503. (No model.)

To all whom it may concern:

Be it known that I, HOMER LITCHFIELD, a citizen of the United States, residing at North Adams, in the county of Berkshire and State 5 of Massachusetts, have invented new and useful Improvements in Let-Off Mechanism for Looms, of which the following is a specification.

This invention relates to looms, and has for 10 its object to provide novel means for automatically letting off the warp-yarn from the warp-beam. This object I accomplish by the combination of devices hereinafter described and claimed, reference being made to the accompanying drawings, in which—

Figure 1 is a side elevation of a portion of a loom-frame, showing the invention applied thereto. Fig. 2 is a detail perspective of the curved shoe or yoke composing a part of the 20 friction let-off devices.

In the drawings, the reference numeral 1 designates a pulley upon a shaft, 3^a, which has a pinion, 1^a, engaging a gear-wheel, 1^b, on the shaft of the warp-beam 2, and 2^a indicates the whip-roll. The shaft of the warp-beam is supported in a loom-frame, 3, in the usual manner, or substantially so, and need not differ in essential particulars from those 25 already known. The pulley is of any suitable 30 dimensions, is made of cast-iron or other metal, and has a perfectly smooth plain periphery, similar to that on ordinary belt-pulleys; but it may have flanges on both sides to keep the strap in place.

Overhanging the pulley 1 is a curved shoe 35 or yoke, 4, having an inner concave surface, which is curved to approximate the surface of the pulley, which is partly surrounded by said shoe. One end, 5, of the latter is bent 40 outward and provided with an eye, 6, which receives a pivot-bolt, 7, passing into a part of the loom-frame, and giving suitable support to the shoe at that end, leaving the other 45 end free to rise and fall, the latter end being weighted, as at 8, so that the shoe is normally drawn down toward the pulley 1. The whip-roll 2^a is provided with a projecting arm, 5^a, from which is suspended a vertical rod, 12, carrying at its lower end a weight, 8^a, and 50 provided with a loop, 11, from which a finger, 10, projects into a vertical slot, 9, in the weighted free end of the curved shoe or yoke.

Drawn around the face of the pulley 1, under the shoe or yoke, is a strap, 13, one end of which is fastened to a stud or projection, 55 14, upon the loom-frame 3, while the other end is secured to the free end of the shoe 4, the length of the strap being such that it may be subjected to tension upon the periphery of the pulley 1 by lowering the weighted end of 60 the shoe, and such tension increased to the maximum, thereby bringing the curved face of the shoe down upon and into contact with the strap 13.

In operation the additional tension on the 65 warp-yarn incident to the shedding motion produced by the usual loom-harness-operating mechanism—for example, as disclosed by Letters Patent No. 64,147—acts on the whip-roll 2^a, raising the arm 5^a with the weighted rod 70 12, thereby lifting the curved shoe or yoke 4 and relieving the pulley 1 from the friction of the strap 13, thus allowing the yarn-beam to turn until sufficient warp is let off. When this is effected, the weighted rod 12 descends and 75 moves the shoe or yoke toward the pulley 1, and thus draws the strap 13 into close frictional contact with said pulley to stop the let-off and hold the yarn-beam firm, thereby producing tension on the warp-yarn, as in the 80 patent named.

I do not broadly claim an automatically-operated brake acting on a pulley for holding and releasing the warp-beam; but

What I do claim is—

In a let-off mechanism for looms, the combination, with the loom-frame, a warp-beam; a pulley geared thereto, and the whip-roll, of a shoe or yoke overhanging the pulley and pivoted at one end to the loom-frame and provided at its free end with a weight and a slot, a flexible friction-strap extending around the pulley under the shoe or yoke and fastened at one end to the loom-frame and at the other end to the weighted free end of the shoe or 95 yoke, and a weight-rod having a finger engaging the slot of the shoe or yoke to loosen and tighten the strap, substantially as described.

In testimony whereof I affix my signature in presence of two witnesses.

HOMER LITCHFIELD.
